UNITED STATES PATENT OFFICE

BESSIE ELLIS GERLACH, NÉE PARKER, AND HUGO GERLACH, OF LONDON, ENGLAND

TYPE CLEANING INSTRUMENT

Application filed July 8, 1929, Serial No. 376,695, and in Great Britain August 3, 1928.

This invention relates to the cleaning of the type of printing apparatus, such for instance, as typewriting machines, cash registers, steel duplicating machines or stamps.

5 For effecting this cleaning, a type cleaning paste has been provided which is of a plastic nature and which has been made up in the shape of cakes or flat plugs.

These plugs are used by dabbing them with 10 the necessary pressure upon the type, using the fingers for this purpose which is an unpleasant and dirty process.

The object of the present invention is to enable users of typewriters and other analogous machine to clean the type of the machine by means of cleansing paste in a convenient and practical way without soiling the hands.

In order that the invention may be more 20 clearly understood, it will now be described with reference to the accompanying drawing in which:—

Fig. 1 shows one form of a complete instrument or apparatus suitable for cleaning 25 the type of one kind of typewriting machine;

Fig. 2 shows another form of instrument of somewhat different design suitable for use with a different kind of typewriting machine.

Fig. 3 is a detail sectional view.

Referring to Fig. 1, *a* is a rotary body, spool or bobbin which is preferably made of boxwood or hard wood of a similar character so as to prevent damage to the types in case of wrong handling. The wood also 30 gives the desired surface to hold the cleaning material *b* which is a chemical preparation of a plastic nature applied to the periphery of the spool or bobbin between the flanges thereof. The bobbin is provided with a metal longitudinally extending bearing tube *h*. *i* is a spindle upon which the bearing tube *h* is mounted to rotate. One end of the spindle *i* is inserted into a wooden handle *m* and held by screws *l* and *k* in the desired 40 position.

The cleaning material used may be of any suitable composition. One such is composed of clay, flowers of sulphur, zinc oxide, corn flower, glycerine, lanoline, starch paste, colophonium, pulverized paragon rubber, talc 50

and glycerine. Any suitable material may be used within the scope of our invention.

On the periphery of the wooden handle *m* is a longitudinally extending incision which forms a rest for an arm *e* and protects it from 55 any lateral movement.

The screws *l* and *k* hold both the arm *e* and the spindle *i* in a firm and reliable position.

The arm *e* is bent as shown so as to form a kind of bridge carrying the spindle of the 60 paste levelling roller *f*. This roller, which is of metal, has a concave longitudinally extending peripheral depression and is of such length as to extend between the flanges of the bobbin *a*. *g* and *g'* are distance tubes 65 for preventing lateral movement of the levelling roller, and to ensure it engaging into the rabbet of the bobbin *a*.

The arm *e* is of resilient material so that by pressing upon it the portion carrying the 70 levelling roller can be pressed down, thus increasing the pressure of this roller upon the surface of the paste.

c is a knob in connection with the outer flange of the bobbin for enabling the bobbin 75 to be rotated on the spindle *i*.

The operation of the instrument is as follows.

The cleansing material as previously stated is laid or coated upon the peripheral 80 channel of the bobbin *a*. The bobbin is then rotated or rolled upon the types. This produces a tendency for the cleaning material to be pushed sideways, which tendency is counteracted by the levelling roller since while the instrument is being used and rolled over the type, the levelling roller in contact with the paste is continually causing the said cleaning material to be fed from the sides towards the middle of the periphery of the 85 spool or bobbin. In order to increase this action when desired the resilient bridge carrying the levelling roller is pressed down and the spool or bobbin *a* is rotated by means of the knob *c*. It is found in practice that 90 by thus rotating the bobbin in contact with the levelling roller after each cleaning operation, fresh cleaning material is brought from the sides to the centre of the periphery, so that unused material comes automatically to 95

100

the surface, and this process may be repeated until every atom of the paste has been used equally.

The form of the instrument illustrated in Fig. 2 is similar to that described with reference to Fig. 1 in all essential details except that the spindle *i* and the bearer arm *e* are cranked or bent, enabling the bobbin *a* carrying the cleaning material *b* to be inserted into the machine so that the cleaning material can be brought into contact with the type.

For other kinds of typewriters or machines appropriate modifications as to constructional details would be made.

It is to be observed that the rotary body or bobbin *a* can be removed and replaced by a fresh bobbin. To effect this the screw *k* is loosened so that the bearing arm *e* can be raised from its position and the levelling roller disengaged from between the flanges of the bobbin. The bobbin can then be slipped off the spindle *i* and replaced by a new bobbin having fresh paste on its periphery. When the bobbin is in position, the screw *k* is tightened down again and the levelling roller engages with the bobbin and the instrument is ready for use.

In case the material *b* is at any time placed or brought into such position as to prevent the bobbin revolving, the arm *e* being resilient the user can level the material by means of pressing lightly on the bearing bridge of the arm *e* and turning the bobbin by means of the knob *c* as previously explained.

What we claim and desire to secure by Letters Patent of the United States of America is:—

1. A type-cleaning instrument including in combination a handle, a rotatably mounted bobbin carrying a body of type-cleaning material, and a roller having inwardly tapered end flanges pressing upon the surface of the material and adapted to feed the material from the end towards the middle of the bobbin.

2. A type-cleaning instrument including in combination a handle carrying a spindle, a flanged bobbin provided with a body of type-cleaning material around its periphery between the flanges, mounted upon the spindle, a resilient bearing arm carried by the handle and extending parallel to the axis of the bobbin, and a roller having tapered end flanges carried by the said bearing arm and adapted to press between the flanges on the bobbin and into contact with the cleaning material.

3. A type-cleaning instrument as claimed in claim 1 wherein the outer flange of the bobbin is provided with a knob for the purpose of rotating the bobbin.

4. A type-cleaning device combining a handle, a rotatable type-cleaning member mounted on the handle and having a plastic

material thereon and means mounted on said handle adapted on rotation of the cleaning member to reform the plastic and thereby present fresh surfaces of the plastic for application to the type.

5. A type-cleaning instrument including in combination a handle, a bobbin coated with type cleaning material rotatable on said handle, the said bobbin being adapted to be rolled with the cleaning material in direct contact with the type, and means carried by said handle for levelling the surface of the cleaning material.

In witness whereof we affix our signatures.
